INVENTOR

William Corman

United States Patent Office.

WILLIAM GORMAN, OF NEW BRITAIN, CONNECTICUT, ASSIGNOR TO THE RUSSELL AND ERWIN MANUFACTURING COMPANY OF SAME PLACE.

Design No. 3,608, dated August 10, 1869.

DESIGN FOR A DOOR-ESCUTCHEON.

The Schedule referred to in these Letters Patent and making part of the same.

To all whom it may concern:

Be it known that I, WILLIAM GORMAN, of New Britain, in the county of Hartford, and State of Connecticut, have originated and designed a new Design for Door-Escutcheon; and I do hereby declare that the following is a full, clear, and exact description thereof, reference being had to the drawing accompanying and making a part of this specification.

The accompanying drawing exhibits a design for a door-escutcheon, after the Assyrian style of ornamentation. The edge is surrounded by a raised band or moulding, *a*, and a similar band, *c*, surrounds the recess for the knob-escutcheon. The angle formed at the junction of that portion of the escutcheon which belongs to the knob and that portion which belongs to

the key-hole, is filled by two supporters, *A A*. The two circular bands formed around the recess for the knob-escutcheon, are connected by ornamental work, as shown.

A device, *C*, in character with the rest of the design, surmounts the whole.

What I claim as my invention, and desire to secure by Letters Patent, is—

The ornamental design for a door-escutcheon, substantially as described, and shown in the drawing.

WILLIAM GORMAN.
